(57) **CLAIM**

The ornamental design for a waste receptacle, as shown and described.

DESCRIPTION

FIG. 1 is a front perspective view of a waste receptacle showing our new design;
FIG. 2 is a rear perspective view thereof;
FIG. 3 is a top plan view of the waste receptacle;
FIG. 4 is a bottom plan view of the waste receptacle;
FIG. 5 is a front elevational view of the waste receptacle;
FIG. 6 is a rear elevational view of the waste receptacle;
FIG. 7 is a right side elevational view of the waste receptacle; and,
FIG. 8 is a left side elevational view of the waste receptacle. Features shown in broken line or bounded by broken line form no part of the claimed design.
